CIGAR PIERCING MACHINE

Thure W. Alm, Stewart Manor, Long Island,
N. Y., assignor to International Cigar Machinery Company, a corporation of New Jersey

Application June 10, 1936, Serial No. 84,408

21 Claims. (Cl. 131—255)

This invention relates to cigar machines, and more particularly to improved machines for piercing the ends of cigars to obviate the necessity for a smoker biting or cutting off the end prior to smoking, and also, to provide an additional draft in each cigar pierced.

While cigar piercing is not new in the art, the existing devices have had many disadvantages which applicant has overcome. It has been found that when fresh cigars are pierced by reciprocating, or rotary and reciprocating needles, there is a tendency for the pierced hole to fill up and close after withdrawal of the piercing means. Where cigars have dried out and are similarly treated large numbers are split and destroyed by the piercing members and rendered unsaleable. Insofar as hollow or tubular piercers or drills have been used, only simple manual devices such as carried by individual smokers or located on store counters have been available. Also, due to the construction of these devices it has been extremely difficult to properly center cigars, with the result that the danger of destroying the fragile ends of cigars was always present during the piercing or drilling operations. Also, in existing forms of piercers, no means has been provided for removing from the opening any scrap or dust tobacco that may have been present or formed therein by the piercer. Obviously, this would result in considerable annoyance when the smoker in smoking his cigar would take these small particles into his mouth.

According to this invention, these disadvantages are overcome since means are provided for properly centering and locating cigars to be pierced and means for piercing a single cigar or a plurality at the same time. Also, means are provided for removing scrap and dust tobacco from the interior of the cigar after the piercing operation, thereby leaving each cigar with a rounded, clean pierced opening, and an unbroken end.

It is therefore the main object of this invention to provide a cigar piercing machine which will more effectively pierce cigars than any device heretofore known.

It is a further object to provide a plurality of devices for simultaneously piercing a plurality of cigars.

It is an additional object to provide piercing devices for piercing a plurality of cigars simultaneously and to furnish means for cleaning said devices of all scrap and dust tobacco following the piercing operation.

It is a further purpose of this invention to fur-

nish a device with a single or a plurality of piercers for piercing the ends of cigars without damaging them, means for cleaning the piercers following the piercing operation, and means for removing from the interior of pierced cigars dust and scrap tobacco produced by the piercers.

It is an additional object to provide a plurality of rotary, tubular drills adapted to be moved in unison into a plurality of aligned cigars for piercing the ends thereof simultaneously.

A further object is to provide positioning and centering devices for properly positioning cigars to be pierced so that the piercers enter the ends of cigars on the exact center line thereof, without fracturing said ends during this operation.

An additional object is to furnish movable positioning members which are provided with associated means for forcing a gaseous fluid blast out of bores formed in said members to expel scrap and dust tobacco from the interiors of cigars or similar articles.

It is a further object to provide a plurality of individual resiliently mounted positioning members for moving cigars into piercing position, in which said members are capable of positioning cigars which may vary somewhat in length.

With these and other objects not specifically mentioned in view, the invention consists in certain steps and constructions which will be hereinafter fully described and then specifically pointed out in the claims hereto appended.

In the accompanying drawings:

Fig. 1 is a side elevation of the improved cigar piercing machine seen from line 1—1 of Fig. 2;

Fig. 2 is an end elevation of the same, on line 2—2 of Fig. 1;

Fig. 3 is a side elevation of the piercing mechanism, on line 3—3 of Fig. 4;

Fig. 4 is a top view of the mechanism shown in Fig. 3; and

Fig. 5 is a perspective view of one of the hollow drills shown in Figs. 3 and 4.

Referring to Figs. 1 and 2, end frames 6 and 7, held together by tie bars 8, 8' and tie bolts 9, 9', 9'', carry a cam shaft 10, a fulcrum shaft 11, and support a top plate 12 and a frame 13, the former supporting a table 14 for the cigars to be pierced and a channel 15 for the pierced cigars, while the latter carries the piercing mechanism 16 which occupies the space between the table 14 and the channel 15 and is arranged to simultaneously operate on a number of cigars.

Cross bars 17 held by the end frames 6 and 7 support a motor 18 which by a belt 19 drives a pulley 20 on a sleeve 21 of a shaft 22 journaled in

a lug 23 of end frame 7 and in a gear housing 24 attached to frame 7. To the pulley 20 is attached a pulley 25 driving, by a belt 26, a pulley 27 on a countershaft 28 supported by a bearing 29 attached to tie bar 8' and by a block 30 fastened to frame 13. Sleeve 21 also carries one members 31 of a clutch the other member 32 of which is movable against a spring 33 by a fork lever 34, on a key 35 of shaft 22. The lever 34 is fulcrumed on a lug 36 of gear housing 24 and is operated through a connecting rod 37, a bell crank lever 38 pivoted on a bracket 39 attached to housing 24, a connecting rod 40, lever 41 pivoted on shaft 11, and through a link 42, by a treadle 43 mounted on tie bolt 9'. Within the housing 24, the shaft 22 carries a worm 44 meshing with a worm-wheel 45 on cam shaft 10 on which are mounted two cams 46 and 47 engaging with rollers 48 and 49 carried by levers 50 and 51, respectively. The levers 50 and 51 are fulcrumed on shaft 11 and are held against their cams by springs 52 and 53 anchored to a bar 54 attached to bearing 29. On the cam shaft 10 is also mounted an arm 55 engageable with a collar 56 on the piston rod 57 of a pump 58 of suitable design, attached to end frame 6, so that the said piston rod is pulled out against a spring 59 once in every revolution of cam shaft 10, this spring, upon the passage of arm 55, pushing the piston rod 57 inward and causing a puff of air to issue from the pump. Collar 56 is adjustably mounted upon rod 57 so that the amount of air necessary to remove scrap and dust from pierced cigars may be definitely controlled.

The piercing mechanism, Figs. 3, 4 and 5, consists of a slidable cigar positioning block 60 containing a number of resiliently mounted plungers 61, of a stationary centering block 62 containing an equal number of coaxial centering rings 63, and of a slidable holder 16 carrying a number of hollow drills 64. The members 16, 60 and 62 are mounted upon a pair of guide rods 65 fast in the end-walls of frame 13, the stationary member 62 being held thereon by set screws 66 while the slidable members 16 and 60 are equipped with bushings 67. The block 60 is actuated by lever 50 through an adjustable connecting rod 68, and the holder 16 by lever 51 through a link 69. The positioning plungers 61, which are hollow, may be provided with cupped faces and are held in their outermost position against their fastening collars 70 by springs 71. Enclosing the collars 70, a casting 72 is fastened to block 60 and connected by a flexible pipe 73 to the outlet of pump 58.

The hollow drills 64 carry fixed gear wheels 74 which intermesh with one another and hold the drills in position in the holder 16. The middle drill 64' is connected by a coupling 75 to a hollow shaft 76 slidable in the block 30 and driven by a pulley 77 connected by a belt 78 with a pulley 79 on countershaft 28. The shaft 76 has a long keyway 80 which engages with a key 81 in pulley 77, thus driving the drills 64 in any position of slide 16. Each of the hollow drills 64 rides on a stationary pin 82 of such length as to protrude a short distance from the working end of the drill in its non-operative position, as shown in full lines in Fig. 3. Thus, when receding from their operating position shown in dotted lines, the drills are automatically cleaned of scrap and dust remaining in their bores. The pins 82 are held in place by clamps 83 attached to the right-hand end wall 13' of frame 13, the pin 82' for the middle drill 64', which is long enough to pass through the drive shaft 76, being held by a clamp 83' on a

5 bracket 84 attached to block 30. The hollow drills 64 which are revolved at a comparatively high rate of speed, are provided with sharpened cutting edges 85, Fig. 5, so that they enter the cigars easily without tearing the wrapper, thereby keeping spoilage down to a minimum.

While being pierced, the cigars rest on grooved guides 86 supported by a stand 87 attached to frame 13. The scrap removed by the pins 82 falls into a chute 88 attached to the base of frame 13 and is by the latter delivered into containers 89 slidably held below the ends of chute 88 by rails 90 attached to the under side of top plate 12.

In the manipulation of this machine, the operator, seated at the machine (facing Fig. 2), with her left hand takes the required number of cigars C—five in the illustration shown—from the supply on table 14 and rolls the same into the grooves of the guides 86 while with her right hand she transfers the cigars C' just pierced into the delivery channel 15, as shown by arrows in Fig. 2. She then releases the treadle 43, whereupon the cam 46 first causes the lever 50 to advance the positioning block 60 into the dotted position 60' shown in Fig. 3, thereby causing the plungers 61' to push the heads of the cigars C into the centering rings 63, and then the cam 47 through lever 51 moves the holder 16 into the dotted position 16' causing the drills 64 to pass through the centering rings 63 and to penetrate into the cigars to the desired distance. The continued action of the cam 47 then moves the holder 16 back into starting position, thereby withdrawing the piercing drills, which are cleaned out by sliding along the pins 82. Upon the withdrawal of the drills, the engagement of the arm 55 with the collar 56 on piston rod 57 causes the pump 58 to send a puff of air by way of pipe 73 and chamber 72 through the hollow plungers 61 into the cigars C, thereby removing scrap and dust produced by the piercers. The action of cam 46 on the lever 50 finally restores the block 60 into its starting position, thereby releasing the pierced cigars, which are then transferred by the operator to the delivery channel 15, while simultaneously forwarding a new lot from table 14 into the vacated spaces.

While one particular embodiment of the invention has been shown and described, it is to be understood that various changes and modifications may be made in the machine without departing from the spirit of the invention, the scope of which may be determined from the appended claims.

What is claimed is:

1. In a device for piercing cigars, a support for a plurality of cigars, a plurality of movable resiliently mounted positioning plungers mounted adjacent one end of said support, a plurality of rotary piercing members located adjacent the head ends of said cigars, means for moving said plungers to position said cigars for piercing, and means for moving said members relative to said cigars for piercing the head ends thereof.

2. In a device for piercing the heads of cigars, means for supporting a plurality of cigars, a plurality of rotary piercing members, a plurality of movably mounted positioning plungers, means for moving said plungers to position said cigars adjacent said members, means for moving said members relative to said cigars to pierce the heads thereof, and mechanism for removing dust and scrap tobacco from said cigars following the piercing operation.

3. In a device for piercing the heads of cigars, means for supporting a plurality of cigars, a plu-

rality of rotary piercing members, a plurality of movably mounted positioning plungers, means for moving said plungers to position said cigars adjacent said members, means for moving said members relative to said cigars to pierce the heads thereof, and mechanism for removing dust and scrap tobacco from said cigars following the piercing operation, said mechanism comprising intermittently operating pneumatic means for forcing a gaseous fluid through said cigar.

4. In a device for piercing the heads of cigars, means for supporting a plurality of cigars, a plurality of rotary piercing members, a plurality of movably mounted positioning plungers, means for moving said plungers to position said cigars adjacent said members, means for moving said members relative to said cigars to pierce the heads thereof, and mechanism for removing dust and scrap tobacco from said cigars following the piercing operation, said mechanism comprising a housing surrounding said positioning plungers, a pump, and means for operating said pump in timed relation to said piercing members for ejecting said dust and scrap from said cigars.

5. A cigar piercer comprising a support for cigars to be pierced, a cigar head centering device positioned adjacent one end of said support, and a movable positioning member located at the other end of said support and adapted to move cigars into contact with said device prior to the piercing operation.

6. A cigar piercer comprising a support for cigars to be pierced, a cigar head centering device positioned adjacent one end of said support, a movable positioning member located at the other end of said support and adapted to move cigars into contact with said device, a rotary piercer adapted to pierce the head end of a positioned cigar, and means for moving said piercer into operative contact with said cigar.

7. A cigar piercer comprising a support for cigars to be pierced, a cigar head centering device positioned adjacent one end of said support, a movable positioning member located at the other end of said support and adapted to move cigars into contact with said device, a rotary piercer adapted to pierce the head end of a positioned cigar, and means for removing waste tobacco and dust from said piercer upon its withdrawal from said cigar.

8. In a cigar piercing machine, the combination with a table provided with a plurality of supports for cigars to be pierced, a plurality of centering devices, means for moving cigars positioned in said supports into operative relationship with said devices to center the same for piercing, a plurality of rotary drills simultaneously operating upon cigars in said support, means for rotating said drills, and means for expelling dust and scrap tobacco from said cigars following the simultaneous operation of the several drills.

9. In a cigar piercing mechanism, a support for a cigar to be pierced, a movably mounted rotary piercing device, a cigar end locating member, a movable positioning element adapted to contact with an end of said cigar and move the other end into said member, and means for moving said device and element in timed relation relative to said cigar to locate and pierce the same.

10. A cigar end piercing mechanism comprising a support for a cigar to be pierced, a movably mounted rotary tubular piercer constructed and arranged to move axially with respect to cigars to be pierced, a stationary stripper rod posi-

tioned within said piercer, means for rotating said piercer, and mechanism for imparting relative movement to said cigar and piercer whereby said piercer moves into operative relation with the end to be pierced, said mechanism withdrawing said piercer at the end of the piercing operation whereupon the rod removes any scrap and dust from the interior thereof.

11. A cigar piercing machine comprising, 10 means for supporting cigars to be pierced, a locating device for locating the ends of cigars properly for piercing, positioning members, each being individually resiliently mounted for moving cigars relative to said supporting means into 15 contact with said device, whereby the axes of said cigars are in line with the axes of the piercers, a plurality of rotary piercers, and means to impart relative movement to said piercers and cigars for bringing said piercers into operative 20 relation with the cigars for piercing the ends thereof.

12. A cigar piercing machine comprising, means for supporting cigars to be pierced, a locating device for locating the ends of cigars properly for piercing, positioning members, each being individually resiliently mounted for moving cigars relative to said supporting means into contact with said device, whereby the axes of said cigars are in line with the axes of the piercers, each of said members being provided with a hollow bore and a casing surrounding one end of each of said members, a plurality of rotary piercers, means to impart relative movement to said piercers and cigars for bringing said piercers into operative relation with the cigars for piercing the ends thereof, and means to force a gaseous fluid through said casing and bores into each pierced cigar to remove therefrom any scrap and dust tobacco.

13. In a cigar piercing machine, the combination with means for supporting cigars to be pierced, of a stationary bar provided with a plurality of cigar end centering devices, a slide located adjacent the other end of said cigars, 45 means carried by said slide for positioning said cigars in said devices, a slide carrying a plurality of piercing members, and means for imparting relative movement relative to said cigars and members for piercing the ends of said cigars.

14. In a cigar piercing machine, the combination with means for supporting cigars to be pierced, of a stationary bar provided with a plurality of cigar end centering devices, a slide located adjacent the other end of said cigars, means 55 carried by said slide for positioning said cigars in said devices, a slide carrying a plurality of rotary piercing members, and means for imparting relative movement relative to said cigars and members for piercing the ends of said cigars.

15. In a device for piercing cigars, a support, a movable member, a plurality of hollow piercing devices carried by said member and movable therein, means for moving said devices into piercing position with respect to cigars to be pierced, and stripper means mounted on said support cooperating with said devices to strip the entire interior operative portion of said devices and remove therefrom dust and scrap tobacco retained thereby, during withdrawal of said devices 70 from pierced cigars.

16. A cigar piercing device comprising a movable member, a plurality of rotary, tubular drills carried therein, means for simultaneously rotating said drills, stripper mechanism associated 75 with said drills and adapted to remove therefrom

scrap and dust tobacco, and means for moving said member and said drills into and out of operative position with respect to cigars to be pierced.

17. A cigar piercer unit comprising a stationary support, an axially movable member, a rotary, tubular drill carried by said member, a stationary ejecting rod mounted upon said support and projecting through said drill, and mechanism for rotating and moving said drill longitudinally relative to said rod for piercing a cigar end, and to retract said drill whereby said rod ejects from said drill scrap and dust tobacco.

18. A cigar positioning device comprising a slide, a plurality of individually mounted resilient members carried thereby and provided with cupped positioning faces and hollow bores, a casing covering one end of said members, means for forcing a gaseous scrap and dust tobacco ejecting fluid through said casing and bores, and means for moving said slide to and from positioning location.

19. In a machine for handling elongated tobacco articles, the combination with a support, of means for positioning articles upon said support, said means comprising a movable element, a positioning device mounted upon said element and provided with a bore, a casing covering the fixed

end of said device, and means for forcing a gaseous medium from said casing and bore and into articles positioned on said support to remove from the interiors thereof scrap and dust tobacco.

5 20. In a machine for handling elongated tobacco articles, the combination with a support, of means for positioning articles upon said support, said means comprising a movable element, a positioning device resiliently mounted upon said element and provided with a bore, a casing covering the fixed end of said device, and means for forcing a gaseous medium from said casing and bore and into articles positioned on said support to remove from the interiors thereof scrap and dust tobacco.

10 21. In a cigar piercing machine, the combination with a table provided with a plurality of supports for cigars to be pierced, a plurality of centering devices, means for moving cigars positioned in said supports into operative relationship with said devices to center the same for piercing, a plurality of rotary drills simultaneously operating upon cigars in said support, means for rotating said drills, and means for expelling dust 15 and scrap tobacco from said drills.

20 THURE W. ALM.
